THOMAS MCGHEYNE GUNN, OF NEW LONDON, CONNECTICUT, ASSIGNOR TO ELECTRIC BOAT COMPANY, OF NEW YORK, N. Y., A CORPORATION OF NEW JERSEY.

TORPEDO-LAUNCHING APPARATUS.

1,097,625.

Specification of Letters Patent. Patented May 26, 1914.

Application filed January 4, 1913. Serial No. 740,196.

To all whom it may concern:

Be it known that I, THOMAS MCGHEYNE GUNN, a citizen of the United States, residing at and whose post-office address is 5 New London, county of New London, and State of Connecticut, have invented certain new and useful Improvements in Torpedo-Launching Apparatus; and I do hereby declare the following to be a full, clear, and 10 exact description of the invention, such as will enable others skilled in the art to which it appertains to make and use the same.

The present invention relates to torpedo launching apparatus, whereby a torpedo 15 tube or a number of them may be located nearer the end of the boat than was heretofore practical, and with the additional advantage of permitting such fine and substantially smooth hull lines in submarine 20 boats as to promote their speed and diving possibilities in runs of endurance as well as in warfare.

Heretofore in some submarine boats the forward ends of the torpedo tubes were extended to the bow portion of the boat, but, 25 since the tubes have heretofore been mounted in parallelism with the center line of the boat, this arrangement prevented fine hull lines at this place as a result of the width 30 required there to accommodate the torpedo tubes. In other cases swinging doors in the hull were installed in the firing line of torpedo tubes rigidly mounted in parallelism with the center line of the boat, but 35 then the torpedo tubes either had to be set back in the boat to obtain fine hull lines or else the idea of fine hull lines had to be given up in order to economize in the length of the boat.

40 So far as I am aware, no arrangement has been disclosed in the prior art wherein fine hull lines are obtained at the end of a boat in which the torpedo tubes are intended to be fired underneath the surface of the water, 45 and wherein at the same time the torpedo tubes may be installed well toward the end of the boat to save in the length thereof.

According to my invention, these results are 50 nicely attained by pivotally mounting the torpedo-tubes near the bow, or stern, as the case may be; and especially in my preferred construction by pivotally mounting each torpedo tube near its rear end in such manner as to swing outwardly as a unit with a 55 corresponding movable hull portion into

the opening produced in the hull, whereby in the normal position all the torpedo tubes lie within the boat substantially along the sides of the hull and close to the center line of the boat, while for firing, the torpedo tube is projected outside the normal line of the hull. Furthermore, in this preferred arrangement, the cap is mounted apart from its torpedo tube and swung simultaneously with it in such manner as to always be out of the 60 way of the moving torpedo tube or tubes and also so as to be outside of all the firing lines thereof at the end of the operation. Also, the movable hull portions are so arranged relatively to the rigid portion that 65 normally a substantially uninterrupted outer surface is presented to the water, thereby promoting speed and diving possibilities in the case of submarine boats. In this way also the recurring favorable moments of 70 fire, which usually disappear quickly each time in warfare, are more likely to be sufficient for firing without undue preparation, by reason of the single driving operation required to entirely clear the line of fire of 75 any one of the torpedo tubes, than would be the case if the movements were obtained by separate driving operations. Furthermore, each torpedo tube and the operating mechanism thereof is separate from all the others 80 and independently operable, so that the firing operation is simpler and more direct than would be obtained by a combined arrangement. In devising an arrangement 85 for these purposes, a construction has been obtained which embodies several novel features applicable for discharging torpedoes from torpedo tubes in various installations as well as in submarine boats. For example, the specific form of operating mechanism for swinging a torpedo tube and its 90 cap is serviceable in torpedo launching apparatus of various kinds in boats and other places, whether the torpedo tube is associated with a swinging door or not, and 95 whether the specific kind of torpedo cap disclosed herein or another kind is used. Also, the mounting on which the torpedo tube is 100 swung and through which operating fluid for the discharge of the torpedo is conducted within the tube, is applicable in general to apparatus for discharging torpedoes from swinging torpedo tubes.

In the accompanying drawings, illustrating the preferred form of my invention ap- 110

plied to a submarine boat as an example, Figure 1, represents a sectional plan of a part of the bow showing the upper torpedo tubes on the two sides of the boat, together with the operating mechanism therefor; Fig. 2, is a section on line 2-2 of Fig. 1, showing two superposed torpedo tubes on one side of the boat, wherein the guides for guiding the torpedo tubes in their swinging movements are particularly illustrated; Fig. 3, represents a front elevation of one torpedo tube, particularly showing part of the cap operating mechanism therefor; Fig. 4, represents a rear elevation of two superposed torpedo tubes on one side of the boat; and Fig. 5, is a section, partly broken away, on line 5-5 of Fig. 1, particularly showing the trunnion bearings of a torpedo tube and the devices for discharging the torpedo from its tube.

The fine lines at the end of the boat, tending to promote speed and superior action in diving, are shown in Fig. 1 at the bow of the boat for firing forwardly, although it is to be understood that a similar arrangement may be provided at the stern of the boat for firing rearwardly, the fine lines of this portion also being essential in these respects. The rigid portion of the hull is denoted by 1 and the outwardly movable hull portions are denoted by 2. Each of the movable hull portions lies closely against the side of the hull so as to be capable of swinging outwardly therefrom about the center of movement of the corresponding torpedo tube, and so as to normally form with the rigid hull portion a substantially smooth or uninterrupted outer surface.

It is usual to provide a plurality of torpedo tubes in a submarine boat, and my invention lends itself to the simultaneous or collective movement of the torpedo tubes to their respective firing positions, although it appears preferable to preserve the simplicity and directness of the firing operation by providing a movable hull portion for each torpedo tube separate from each of the others and independently operable. Therefore, I show four torpedo tubes 3, two being arranged in superposed relation on each side of the longitudinal center line of the boat, wherein the operating mechanism for each torpedo tube is intended to be actuated independently of that for the other tubes.

Each torpedo tube 3 is mounted on trunnions near its rear end, and is rigidly connected to a movable hull portion 2 by the metal section 4. The forward end of the torpedo tube carries a collar 5 fastened to the movable hull portion 2 and adapted to slide in guides 6 for guiding the torpedo tube and the movable hull section in their swinging movements. In the normally-closed position, the torpedo tubes lie within the boat along the hull and close to the lon-

gitudinal center line of the boat, as shown in full lines in Fig. 1, while for firing, each torpedo tube and the corresponding movable hull portion is swung outwardly and the torpedo tube itself is swung into the opening in the hull produced thereby to the position indicated by the broken lines in Fig. 1. In the normal position, a cap 7 fits over the forward end of each torpedo tube. Simultaneously with the movement of a tube the corresponding cap is swung about a stationary pivot in such manner as always to be out of the path of the tube and of all the other tubes, and finally so as to be entirely outside the line of fire. It is apparent that the torpedo tubes may be swung into firing line with the respective openings produced in the hull without actually being projected thereinto, although the illustrated construction is to be preferred where it is desirable to compact the torpedo tubes so far as possible in the end of the boat.

Independent operating mechanism for moving the parts is provided for the torpedo tubes, and the arrangement is such that none of the parts of one unit interferes with the operation of any of the others or projects within any of the firing lines. The preferred form of each operating mechanism includes a shaft 8 properly journaled, and extending from suitable driving means within the submarine boat to the torpedo tube cap. This shaft carries a worm 9 in engagement with a toothed segment 10, which is coupled to an operating connection 11 pivoted to the torpedo tube near the rear end thereof. Screw threads on the forward end of the shaft 8 engage a square nut 12, which is held against rotation by an operating arm 13 fastened on a shaft 14 carrying the cap 7. (See Fig. 3.) Thus when the shaft is rotated by suitable driving mechanism (not shown) the torpedo tube is swung on its trunnions, thereby swinging the movable hull portion outwardly at the same time that the torpedo tube is being swung into the opening in the hull produced thereby to a clear firing position substantially in line with the direction of motion of the boat. At the same time the cap 7 is being swung so as to continually be out of the way of the moving torpedo and so as to be outside of the firing line of the torpedo tube at the end of the operation.

The bearing in which each torpedo tube is mounted comprises cupped sections 15 embracing an enlargement 16 of spherical form on the torpedo tube near the rear end thereof. The cupped sections are provided with vertical trunnions 17 extending within shaped cavities in the spherical part of the tube to permit horizontal swinging movements of the torpedo tube. (See Fig. 5.) A conduit extends through the upper trunnion from a point within the torpedo tube 130

and near the rear end thereof to a connection with a valve in a pipe 18 leading from a source of operating fluid, in order to conduct the operating fluid to a point behind the torpedo 19 for discharging the torpedo from its tube. A grease cup 20 is provided for lubricating the friction surfaces. The rear caps 21 for the torpedo tubes are of the ordinary form.

Having thus described my invention, what I claim is:—

1. The combination with a torpedo boat, of a torpedo tube permanently pivoted within the hull of the boat and designed to swing away from the center line thereof from a housed position within the lines of the hull to a firing position with its discharge end outside of the lines of the hull, and mechanism for swinging the torpedo tube on its pivot between said housed position and said firing position; substantially as described.

2. The combination with a boat having a rigid hull portion, and a movable hull portion adapted to be projected outwardly from the rigid hull portion to produce an opening in the hull suitable for the discharge of a torpedo therethrough, of a torpedo tube pivotally mounted within the boat, and means for moving the movable hull section outwardly and for swinging the torpedo tube into firing line with the opening in the hull produced thereby; substantially as described.

3. The combination with a boat having a rigid hull portion, and a movable hull portion adapted to be swung relatively to the rigid hull portion to produce an opening in the hull suitable for the projection of a torpedo tube thereinto, of a torpedo tube pivotally mounted within the boat in such manner as to normally lie within the normal hull line of the boat, and means for swinging the movable hull portion and for swinging the torpedo tube into the opening in the hull produced thereby; substantially as described.

4. The combination with a boat having a rigid hull portion, and a movable hull portion adapted to be projected outwardly from the rigid hull portion to produce an opening in the hull suitable for the projection of a torpedo tube thereinto, of a torpedo tube pivotally mounted within the boat in such manner as to normally lie within the normal hull line of the boat, and means for moving the movable hull portion outwardly and for swinging the torpedo tube into the opening in the hull produced thereby; substantially as described.

5. The combination with a boat having a rigid hull portion, and a movable hull portion near one end of the boat arranged relatively to the rigid hull portion in such manner as to present a substantially uninterrupted outer surface when in its nor-

70 rupted outer surface when in its normally-closed position and adapted to be swung outwardly from its normally-closed position to produce an opening in the hull suitable for the projection of a torpedo tube thereinto, of a torpedo tube pivotally mounted within the boat in such manner as to normally lie within the normal hull lines of the boat, and means for swinging the movable hull portion outwardly to its open position and for 75 swinging the torpedo tube into the opening produced thereby; substantially as described.

6. The combination with a boat having a rigid hull portion, and a movable hull portion adapted to be moved outwardly relatively to the rigid hull portion to produce an opening in the hull suitable for the discharge of a torpedo therethrough, of a torpedo tube pivotally mounted within the boat 80 and connected to the movable hull portion, and operating mechanism for swinging the movable hull portion and the torpedo tube at the same time for the purpose of producing an opening in the hull and simultaneously swinging the torpedo tube into firing line therewith; substantially as described.

7. The combination with a boat having a rigid hull portion, and a movable hull portion near one end of the boat arranged relatively to the rigid hull portion in such manner as to present a substantially uninterrupted outer surface when in its normally closed position and adapted to be swung outwardly from its normally-closed position to produce an opening in the hull suitable for the projection of a torpedo tube thereinto, of a torpedo tube pivotally mounted near its rear end in such manner as to normally lie within the normal hull lines of the boat 100 and connected to the movable hull portion to swing therewith as a unit, and operating mechanism for swinging the movable hull portion to its open position and for simultaneously swinging the torpedo into the 105 opening produced thereby; substantially as described.

8. The combination with a boat having a rigid hull portion, and a movable hull portion adapted to be moved relatively thereto 110 in such manner as to produce an opening in the hull suitable for the discharge of a torpedo therethrough, of a torpedo tube pivotally mounted within the boat and having a cap at its forward end, and operating mechanism for moving the parts to such positions that the torpedo tube is in firing line with the opening in the hull while the cap is outside of that line; substantially as described.

9. The combination with a boat having a rigid hull portion, and a movable hull portion near one end of the boat arranged relatively to the rigid hull portion in such manner as to present a substantially uninterrupted outer surface when in its nor- 115

1. mally closed position and adapted to be swung outwardly from its normally-closed position to produce an opening in the hull suitable for the projection of a torpedo tube 5 thereinto, of a torpedo tube pivotally mounted near its rear end in such manner as to normally lie within the normal hull lines of the boat and rigidly connected to the movable hull portion to swing together as a unit,
10. a torpedo cap disconnected from the torpedo tube and adapted to fit over the forward end thereof in the normal position of the parts, and operating mechanism for swinging the movable hull section to its open position and 15 simultaneously swinging the torpedo tube into the opening produced thereby, the cap being simultaneously swung out of the path of the torpedo tube and out of the firing line thereof at the end of the movement; substantially as described.
10. In apparatus for launching torpedoes, the combination of a torpedo tube mounted for swinging movement about a point near its rear end, and a torpedo tube cap adapted 25 to cover the forward end of the torpedo in the normal position thereof and mounted to swing about a fixed center, of operating mechanism for swinging the torpedo tube into a firing position and for swinging the 30 torpedo tube cap about its center so as to extend outside of the path of the torpedo tube and to be outside of the firing line of the torpedo tube in the firing position thereof; substantially as described.
35. 11. In an apparatus for launching torpedoes, the combination of a torpedo tube mounted for swinging movement about a point near its rear end, and a torpedo tube cap adapted to cover the forward end of the 40 torpedo in the normal position thereof and mounted to swing about a fixed center, of operating mechanism for swinging the torpedo tube into a clear firing position, comprising a rotatable shaft, a gear fastened on 45 the shaft, an operating connection connected to the torpedo tube, a segment coupled to the operating connection and in driving engagement with the gear, a nut engaging screw

threads on the shaft, and an operating connection between the nut and the torpedo tube cap, whereby when the torpedo tube is being swung to its firing position the cap is being swung out of the path of the torpedo tube in such manner that at the end of the operation the cap is outside of the line of fire of the torpedo; substantially as described.

12. The combination with a torpedo tube pivotally mounted near its rear end, and operating mechanism for swinging the torpedo tube, of a supporting guide near the forward end of the torpedo tube for supporting and guiding the forward end of the torpedo tube in its swinging movement; substantially as described.

13. The combination with a boat having a rigid hull portion and an outwardly movable hull portion adapted to be swung to an open position relatively thereto to produce an opening suitable for the projection of a torpedo tube thereinto, of a torpedo tube pivotally mounted within the boat and fastened to the movable hull portion, a guide for the torpedo tube, and operating mechanism for swinging the torpedo tube to its firing position, the arrangement being such that the movable hull portion is guided outwardly in its movement to produce an opening in the hull while the torpedo tube is guided to a position in which it projects into the opening; substantially as described.

14. The combination with a torpedo tube, of trunnions for supporting said torpedo tube for swinging movement, one of said trunnions having a conduit passing from within the torpedo tube to a connection with a source of operating fluid for discharging the torpedo from within the torpedo tube; substantially as described.

In testimony whereof I affix my signature, in presence of two witnesses.
